(57) **CLAIM**

The ornamental design for a component of a trigger mechanism for a firearm, as shown and described.

DESCRIPTION

FIG. 1 is an isometric view of a component of a trigger mechanism for a firearm;

FIG. 2 is a front elevation view of the component of a trigger mechanism for a firearm of FIG. 1;

FIG. 3 is a rear elevation view of the component of a trigger mechanism for a firearm of FIG. 1;

FIG. 4 is a right side elevation view of the component of a trigger mechanism for a firearm of FIG. 1;

FIG. 5 is a left side elevation view of the component of a trigger mechanism for a firearm of FIG. 1;

FIG. 6 is a top view of the component of a trigger mechanism for a firearm of FIG. 1; and,

FIG. 7 is a bottom view of the component of a trigger mechanism for a firearm of FIG. 1.

The broken lines in the Figures are for illustrative purposes only and form no part of the claimed design.
